FABRIC TENSION CONTROL MEANS FOR
KNITTING MACHINES

Herbert Erich Haehnel, West Reading, Pa., assignor to Textile Machine Works, Wyomissing, Pa., a corporation of Pennsylvania

Application December 29, 1949, Serial No. 135,688

20 Claims. (Cl. 66—149)

1

The present invention relates to full-fashioned knitting machines provided with welt turning mechanism and more particularly to fabric tension control means acting in conjunction therewith.

It has been proposed in connection with welt turners, as in Bitzer Patent No. 2,413,601, December 31, 1946, to employ means for moving the welt wire in the draw-off direction including two motor means, one for actuating said moving means to apply its draw-off tension to the welt wire somewhat before and for a while after the loops of the first course of a stocking blank have been returned to the needles to turn or close the welt, and the other actuating said moving means to apply its draw-off tension to the welt wire from a time somewhat after the welt has been turned and until the blank has been finished.

According to the arrangement of said patent, the change from one motor means for the welt wire moving means to the other is accomplished by devices actuated directly by the first motor means. This arrangement, while being reliable in its operation, nevertheless, is inflexible in its time of operation due to requirements of other operating parts of the welt turning mechanism.

It is therefore an object of the present invention to provide an operating mechanism adapted to cooperate with the welt turning means to change from one motor means for the welt wire moving means to another at any one of the several points or times in the cycle of knitting a blank as desired.

It is another object of the invention to provide an improved device adapted to change from one motor means for the welt wire moving means to another which is not only adaptable to operate at a wide variety of times but also operable either just after the welt has been turned or relatively soon after the turning or closing step has been completed.

In the arrangement disclosed in said patent to Bitzer, the weight motor means is activated to apply draw-off tension to the welt wire and the fabric at a predetermined point in the welt fabric knitting cycle and continues to tension the fabric for a predetermined length after the welt is closed and only when the weight motor has completed its determined tensioning cycle may the spring motor means become effective to tension the welt wire. However, under certain knitting conditions it is desirable to vary the time the weight motor means becomes ineffective and the spring motor means becomes effective, or it may be desirable to use the tension of both motor means simultaneously where either motor means

2

is insufficient individually to obtain certain required results.

It is a further object of the invention to provide an arrangement whereby both the weight motor means and the spring motor means may, when desired, act on the welt wire simultaneously to tension the fabric.

It is also an object of the present invention to activate or inactivate either or both weight motor means and spring motor means to control the tensioning action of the welt wire during certain portions of a fabric knitting cycle.

It is a still further object of the invention to provide means for controlling the activation or inactivation of the weight motor means and spring motor means for the welt wire according to a predetermined pattern.

With these and other objects in view, which will become apparent from the following detailed description of the illustrative embodiment of the invention shown in the accompanying drawings, my invention resides in the novel elements, features of construction and arrangement of parts in cooperative relationship as hereinafter more particularly pointed out in the claims.

In the drawings:

Figure 1 is a front elevation of portions of a full-fashioned knitting machine to which the present invention has been applied, parts being broken away and parts being omitted for purpose of illustration;

Fig. 2 is a front elevation on an enlarged scale of a portion of the mechanism shown in Fig. 1, and showing certain parts omitted in Fig. 1;

Fig. 3 is a plan view of a portion of Fig. 2 and also showing other parts not shown in Fig. 2;

Fig. 4 is a view of the mechanism as seen from the left of Fig. 2;

Fig. 5 is a sectional detail view taken substantially along the line 5—5 of Fig. 2;

Fig. 6 is a sectional detail view taken substantially along the line 6—6 of Fig. 1;

Fig. 7 is a sectional detail view taken substantially on the line 7—7 of Fig. 6, looking in the direction of the arrows;

Fig. 8 is a view similar to a portion of Fig. 7 taken substantially on the line 8—8 of Fig. 6;

Fig. 9 is a sectional elevation of certain of the mechanism as viewed from the left of Fig. 1;

Fig. 10 is a sectional detail view taken substantially on the line 10—10 of Fig. 1 looking in the direction of the arrows;

Fig. 11 is a sectional detail view taken substantially on the line 11—11 of Fig. 1 looking in the direction of the arrows; and

Fig. 12 is a transverse sectional view through

the machine showing certain of the loop forming and welt turning elements with which the invention is associated.

In the drawings and description, only the means necessary to a complete understanding of the invention are specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

2. Four catalogs entitled—The "Reading" Full-Fashioned Knitting Machine Parts Catalog—published and copyrighted by the Textile Machine Works, in 1929, 1935, 1940 and 1947, respectively.

3. Booklet entitled—The "Reading" High-Production Full-Fashioned Knitting Machine—which, forming a supplement to the above noted 1940 Parts Catalog of the Textile Machine Works, is a publication of the Textile Machine Works, copyrighted by the latter in 1940.

4. Pamphlet entitled—Knitting Machine Lectures—published by the Wyomissing Polytechnic Institute, Wyomissing, Pennsylvania, in 1935.

In the arrangement shown in Fig. 12 of the drawing, there are included a group of knitting elements of a standard type composed of a needle bar 16 having a row of beard type knitting needles therein, one of which is shown at 17. A sinkerhead 18 mounted on a center bed 20 contains sinkers 21 and dividers 22 for forming loops of yarn about the stems of the needles. Bridge members 25 are provided, two to each knitting section, mounted on a front bed or table 26 and extending transversely to the table and to the needle row. Members 25 serve as tracks or rails for a welt bar 27 having a set of welt hooks 30 thereon of the type shown in a patent to Bitzer No. 2,431,160. The means for moving the welt bar toward the needle row at times of hooking-up and of turning the welt comprises a shaft 31 having levers 32 thereon, two for each knitting section. Levers 32 have links 33 pivoted to their outer ends. The free ends of links 33 have pins 35 fixed therein, pins 35 having a portion resting on the top edges of the bridges and a portion engaging socket members 36 which are fixed to the edge of a welt bar whereby the pins may push the welt bar toward the needle row. For this purpose, the shaft 31 is turned counterclockwise as viewed in Fig. 12, thereby thrusting pins 35 toward the left. Counterclockwise turning movements of shaft 31 are produced by actuating mechanism 34 including a rack bar 39 having rack teeth thereon meshing with a pinion on shaft 31, and actuated by a set of three cams, not shown herein but forming a part of the mechanism in said Bitzer patents hereinbefore set forth. One of said cams moves the pins 35 and welt bar 27 so that the hooks project between the needles to receive the sinker loops of the first course at the time of "hooking up." A second one of said cams moves the welt bar to an intermediate or so-called "half-turn" position and a third cam to affect the position of the welt bar moves it to the same position as at hooking up but has a longer dwell to provide sufficient time in the cycle to ensure proper turning or closing of the welt, that is the returning of the loops of the first course to the needles. The pres-

ent invention has to do principally with conditions and operations related to the operation of said second cam and the resulting "half-turn" position of the welt bar.

5 When the first course of loops on the needles has been engaged with the welt hooks, an auxiliary draw-off means, attached to the welt bar 27, draws the welt bar and hooks away from the needles. This auxiliary draw-off means comprises 10 a weight operated shaft 37 (weight not shown) on which is mounted draw-off reels 38, one for each of the knitting sections, and straps 40 for attaching the reels 38 to the welt bars, each bar 27 having a loop 41 adapted to be engaged with 15 a hook 42 on the free end of a strap 40 to transmit draw-off tension from the strap to the welt bar. After the auxiliary draw-off means has drawn off a certain amount of fabric, welt wires are placed on the fabric on each row of needles 20 in position to be engaged by a main draw-off means as shown in Fig. 12. The main draw-off means comprises a shaft 43 having draw-off reels 45 fixed thereon, straps 46 connected to reels 45, hooks 47 at the free ends of straps 46 for connecting the straps to the welt wire, and two motor means arranged to drive shaft 43 at desired 25 times, preferably one after the other but both motor means may be operated simultaneously as controlled by means hereinafter set forth. For this purpose, there are used a weight actuated 30 motor means 48 and a spring motor means 50, a portion of which is shown in Fig. 1, both arranged and adapted to act to drive shaft 43 in the take-off direction. Only those parts of spring motor means 50 necessary to a complete understanding 35 of the present invention are shown and described herein and a more detailed description of said spring motor means may be had by reference to Richter U. S. Patent No. 2,004,219 of June 11, 1935, Bitzer U. S. Patent No. 2,413,601 of December 31, 1946, the 1940 and 1947 parts catalogs and the supplement to the 1940 catalog, hereinbefore referred to.

40 According to the invention, both weight motor means 48 and spring motor means 50 are controlled as to their times of going into action and their times of going out of action by the usual pattern means of the machine, a known form of which includes an auxiliary pattern device such as that shown at 51 in Fig. 1. Disabling means are provided, one for weight motor means 48 and one for spring motor means 50, the disabling means for weight motor 48, however, being biased to disabling position and rendered inactive at desired times both by the pattern means and by another means to be presently described, while the disabling means for the spring motor 50 is biased to inactive position to permit the motor means 50 to operate except when its disabling means is rendered active by the auxiliary pattern device 51. The weight motor means 48 will be understood to work only a minor portion of the cycle of knitting a stocking blank compared to spring means 50 but both operate to turn the main reel draw-off shaft in the draw-off direction.

45 As shown in Figs. 1, 2 and 7, the weight actuated motor means 48 comprises a sheave 52 pivoted on an axle 53 coaxial with shaft 43 and on 50 which is wound a cable 55 having a weight (not shown) connected thereto in the usual manner, the cable and sheave being arranged to turn the shaft 43 in the desired direction due to torque exerted by the weight in a manner hereinafter set forth. The cable 55 having been wound suf-

fficiently on the sheave 52, the weighted cable drives the sheave and shaft 43 in the draw-off direction for as long as necessary after being rendered active. The driving arrangement between the sheave 52 and shaft 43 is best shown in Figs. 6, 7 and 8 and comprises a pawl 56 pivoted on a pin 57 on the sheave. Pawl 56 engages with a shoulder or notch 58 on a collar 60 fixed on shaft 43 whereby the tension in the cable 55 applies a torque to sheave 52 and through the pawl and collar turns the shaft 43 in the draw-off direction. The pawl 56 is maintained in engagement with shoulder 58 or may be held in inactive position relative to the shoulder by engagement of a spring pressed detent 61 with a flat sided portion 59 of the pin 57 as shown in Fig. 8. Owing to the type of drive shown, shaft 43 can be driven in the draw-off direction by means other than sheave 52 when the sheave is prevented from moving in the draw-off direction, pawl 56 and notch 58 in collar 60 acting as an overdrive for permitting the shaft 43 to run ahead of weight motor 48.

There is provided a pinion 62 secured to a handle member 65 mounted to both slide and rotate on an axle 63 carried in a fixed part of the machine. The pinion 62 is adapted to be engaged with a gear wheel 66 fixed on the shaft 43, the pinion normally being biased to inactive position relative to the gear wheel by a spring 64 as shown in Figs. 1 and 2. In order to wind up the cable 55 and its attached weight, the pinion 62 is engaged with gear wheel 66 and the handle 65 rotated to turn the gear wheel in a counterclockwise direction as viewed in Fig. 4. As the shaft 43 is turned, the shoulder 58 of collar 60 in engagement with the pawl 56, turns the sheave 52 to wind the cable 55 thereon.

Preferably, and as fully shown and described in said Patent No. 2,413,601 to Bitzer, means are provided for moving the hooks 47 on the straps 46 toward the needles, at the same time that the cable 55 is wound upon the sheave 52, into position for subsequent engagement to the welt wire after the welt wire has been placed on the fabric, and only those parts necessary to a complete understanding of the present invention are shown herein. The means shown for this purpose comprises a shaft 67 which extends across all the knitting sections and has fixed thereon at each section a pair of sprocket drums or wheels one of which appears at 68 in Figs. 3 and 12. Each of said wheels has thereon a belt or band 70 extending toward the needles 17 and around an idler 71, the band having holes therein spaced regularly along a portion of its length and adapted to engage projections 72 on the wheel whereby shaft 67 may drive the band 70. A tension spring 73 is connected into band 70 to hold it closely against the sprocket 68 and idler 71. In order to run the straps 46 toward the needle row, the bands 70 have spurs 75 attached thereto adapted to engage in slots in the hook members 47 which are attached to the straps 46. After the hook members 47 have been engaged with spurs 75, the shaft 67 is turned to move said spurs toward the needle row. When the hooks 47 have reached the position, shown in Fig. 12, they are held in such position by a latch pawl (not shown) which engages a notch in a member (also not shown) fixed to shaft 67. With the hooks 47 in the position of Fig. 12 and after a predetermined length of welt fabric is knitted, a welt rod 76 is pressed through spring biased members 77, in the bridge members 25, and into grooves 78 in the bridge members in

position for subsequent engagement with the hooks.

The means whereby shaft 67 is turned comprises, in addition to the means for winding up cable 55, a means shown best in Figs. 2 and 3 and including a clutch member 80 fixed on shaft 43 adapted to coact with a clutch member 81 carried on shaft 43 and arranged to be moved into engagement with member 80 so that member 81 will be driven by member 80 whenever handle 65 is operated to wind up cable 55 on sheave 52. A gear wheel 82 fixed to member 81 is embraced by jaws 83 of a shift member 84 pivoted on a fixed part of the machine so that when it is swung in a counterclockwise direction, as viewed in Fig. 2, the clutch member 80 is engaged to the clutch member 81 to drive gear 82 when pinion 62 is operated. The gear 82 (Fig. 4) meshes with and drives an idler gear 86 and the idler in turn drives a gear 87 on shaft 67 to move the bands 70, straps 46 and hooks 47 of the main draw-off for the welt wire toward the needles 17. A tension spring 88 normally holds member 84 in the position shown in Fig. 2 and at the same time holds member 81 against a collar 90 fixed on shaft 43, as shown in Fig. 2, in which position the clutch members 80 and 81 are disconnected and the shaft 43 is free to turn in the draw-off direction without affecting shaft 67. Normally the weight motor means 48 is held inactive by a disabling means including a pawl 91 which is pivoted on a pin 92 fixed on the frame of the machine and which is biased to engage a toothed surface 93 on sheave 52 by means including a rod 95 pivoted to pawl 91 by means of a pin 96 and a spring 97 (Fig. 6) connected to a hook on the rod and to a fixed point on the frame.

Two means are shown for rendering the pawl 91 ineffective by drawing it away from the toothed portion 93. One of said means for drawing the pawl 91 out of its effective position operates when the straps 46 are being drawn toward the needle row. At this time, the sheave 52 turns counterclockwise as viewed in Fig. 6 so that the teeth on surface 93 of sheave 52 tend to push the pawl 91 away and slide past the pawl. As soon, however, as a movement of shaft 67 occurs, as hereinbefore set forth, pawl 91 is drawn away from sheave 52 by a means including a high portion 98 of a collar 100 (Fig. 5) fixed on shaft 67 and a pivoted bell-crank lever 101, one arm 102 of which rests against the collar 100 while the other arm 103 has a boss 105 at its free end. The boss 105 has an aperture through which the rod 95 passes, the rod having a collar 106 secured thereto adapted to engage the boss 105 as hereinbefore set forth. The collar 100 also has a low portion 107 against which the arm 102 normally rests, as shown in Fig. 5. When shaft 67 turns, as the straps 46 are moved toward the needles 17, the low portion 107 is moved out of engagement with arm 102 and the high portion 98 engages the arm which causes the boss 105 to engage the collar 106 and press the rod 95 downwardly against the tension of spring 97 to draw pawl 91 out of contact with surface 93. Immediately upon disengagement of the pawl 91 from the surface 93, the tension in cable 55 is exerted on shaft 43 and straps 46 through driving pawl 56 and collar 60 (Fig. 6). Movement of the bands 70 and straps 46 toward the needles also winds the cable 55 on the sheave 52 and the straps are held by the spurs 75 on bands 70 against the tension exerted by the cable as long as shaft 67 is held by its latch pawl. After a predetermined

length of welt fabric is knitted the second of the three cams which act at times on shaft 31 comes into play and turns shaft 31 to move the welt bar 27 into its "half-turn" position. Simultaneously, with the movement of the welt bar 27 to the "half-turn" position, a cam (not shown) on shaft 31 disengages the latch and releases shaft 67. Upon release of the shaft 67 means (not shown) turns the shaft to disengage the spurs 75 from the straps 46 and return them to starting position, this action permitting the hooks to be drawn into engagement with and apply tension to the welt rod 76 to form a fold in the fabric as the welt bar 27 advances to the "half-turn" position. As the bands 70 are returned to starting position, the shaft 67 rotates to again move the low portion 107 of collar 109 into engagement with the arm 102 thereby disengaging the boss 105 of arm 103 from the collar 106 on the rod 95 which tends to again permit the pawl 91 to engage the toothed surface 93. However, just prior to the actions set into motion by the advance of the welt bar 27 to "half-turn" position, the rod 95 is operated from the pattern means 51 to maintain the pawl 91 disengaged from the surface 93. Therefore, when boss 105 disengages collar 106, the pawl 91 remains in disengaged position and the straps 46 remain under the tension exerted by cable 55.

The means whereby the auxiliary pattern means 51 maintains pawl 91 in ineffective position comprises, in addition to the usual chain member 108 (Fig. 1) and sprocket wheel 110, shown in dot-and-dash outline, a bell-crank lever 111 pivoted on a shaft 112 carried in a fixed position on the machine and having one arm 113 the lower end of which is connected to a tension spring tending to turn lever 111 clockwise against a stop 115. Arm 113 has a projection 116 thereon adapted to contact buttons (not shown) or the like on the chain 108. The lever 111 has a second arm 117 having an apertured member 118 pivoted at its free end and through which the rod 95 extends. The aperture in the member 118 is countersunk to receive the rounded ends of two collars 120 on rod 95, as shown in Fig. 6, so that the lever arm 117 can rock with respect to the rod. Consequently, when chain 108 has been racked in the usual way until a button comes under projection 116, lever 111 is turned counterclockwise as viewed in Fig. 1 and the arm 117 draws rod 95 downwardly so as to throw pawl 91 into an ineffective position relative to the toothed surface 93 or maintain the pawl in said ineffective position when moved thereto by the lever 101 as hereinbefore set forth. The first button to affect lever 111 is set on chain 108 so that it operates lever 111 just before the draw-off torque produced by weight motor 48 on the straps 46 is thrown onto the welt rods 76 at the "half-turn" operation. A sufficient number of buttons are set on chain 108 to maintain the pawl 91 in ineffective position until the spring motor means 50 is to be thrown into action. As soon as there is no button in engagement with part 116 of arm 113, the spring 97 on rod 95 and the spring on arm 113 cooperates to raise rod 95 and throw pawl 91 into engagement with toothed surface 93 to effectively disable weight motor 48.

Operation of the spring motor means 50 is controlled by a rod 121 which extends longitudinally along the front of the machine. For controlling spring motor means 50, rod 121 is connected to a bell-crank lever 122 having one arm 123 depending from the pivot of the lever

the rounded end of which extends between collars 125 or like members fixed on rod 121 so as to transmit motion from the rod to the lever. Lever 122 has a second arm 126 the free end of which is apertured to permit a rod 127 to extend vertically therethrough. The aperture in the end of arm 126 is countersunk to provide surfaces adapted to cooperate with rounded ends on collars 128 so that arm 126 can rock with respect to rod 127. A tension spring 130 connected between a hooked end on arm 126 and a collar 131 fixed to rod 127 near its lower end holds the end of arm 126 resiliently but firmly in engagement with the lower collar 128, as shown in Fig. 1, so that rod 127 will respond quickly to the movements of lever 122. A tension spring 132 biases rod 121 to the left as viewed in Fig. 1 so that a dog 133 fixed to rod 121 near its right hand end is held in contact with a rounded lower end of a depending lever 135 also forming a part of pattern means 51 and pivoted on shaft 112. Lever 135 is adapted to be turned counterclockwise as viewed in Fig. 1 by buttons on chain 108 similarly to lever 111 and is held against a stop similar to stop 115 by spring 132 at all times when it is not in contact with a button on the chain. When lever 135 is in the position against its stop as shown in Fig. 1, its position when turned in a clockwise direction by spring 132, rod 127 being then elevated, spring motor means 50 is active because of mechanism best shown in Figs. 9, 10 and 11. Said mechanism comprises a cam 136 freely pivoted on shaft 43 and, when rod 127 is elevated, cam 136 stands in the position shown in Fig. 11 in which the spring means turns shaft 43 through an actuating pawl 137 which is biased by a spring 138 into contact with the teeth of a ratchet wheel 140 fixed on shaft 43. The pawl 137 is pivoted on a pin 141 fixed on a lever 142 pivotally mounted on the shaft 43, one end 143 of the lever being connected to a rod 145. The other end of rod 145 is connected to and actuated by means (not shown), as set forth in the patents and publications hereinbefore referred to, to operate the pawl 137 to turn shaft 43 and reels 45 in the clockwise or take-off direction and to turn the lever 142 counterclockwise as viewed in Fig. 10, to permit the pawl to engage a different tooth on ratchet wheel 140 as the fabric is knitted. A series of different length pawls 146 are provided, as shown in Figs. 1 and 10, to engage the teeth of ratchet wheel 140 and prevent rotation of the shaft 43 in reverse to the take-off direction at the time the lever 142 is moved to engage the pawl 137 with a different tooth of the ratchet wheel.

The pawls 146 are pivotally carried on a pin 147 fixed to a part of the machine frame, as shown in Fig. 9, and are biased into engagement with the ratchet wheel 140 by springs 148. The pawls 146 are adapted to engage a portion 150 of a lever 151 also pivoted on the pin 147 for purposes hereinafter set forth. The lever 151 has a sliding connection to one end of a rod 152, the other end of which is connected to the usual front catch bar motion shaft of the machine (not shown) by means of which the rod 152 may be actuated to turn the lever 151 in a counterclockwise direction and through the portion 150 disengage the pawls 146 from the ratchet wheel 140 to relieve the tension of shaft 43 during narrowing cycles of the machine in the usual manner. The lever 151 is also provided with a curved arm portion 153 which is

adapted to be engaged by pawl 137 when it is desired to manually rotate the pawl to inactive position, which action also turns the lever 151 in the counterclockwise direction, as viewed in Fig. 10, to disengage the pawls 146 from the ratchet wheel 140. When, however, a button on chain 108 turns lever 135 counterclockwise, rod 121 is lowered and cam 136 is turned counterclockwise as viewed in Fig. 11, thereby moving a high portion 154 of the cam beneath a stem 156 of a bolt fixed to and extending laterally of pawl 137 (Fig. 1) to disengage the pawl from the ratchet wheel 140. At the same time, a second portion 157 of cam 136 is moved to engage a pin 158 carried on the lever 151 to turn the lever in a counterclockwise direction to disengage the pawls 146 so that the shaft 43 is free of the spring motor means 50 and may again be controlled by the weight means 48 as hereinbelow set forth.

The operation of the apparatus herein described will be obvious to those skilled in the art. For purposes of convenience, however, the description of the operation of the mechanism disclosed herein will be recapitulated as follows: As the first course of loops is being formed, the welt bars 27, under tension of the straps 40, are moved by levers 32 and links 33 by the first of the welt bar operating cams, hereinbefore set forth, toward the needles to project welt hooks 30 between the needles to receive the loops. After the loops are engaged by the hooks 30 the levers 32 and links 33 are returned to the position of Fig. 12 and the loops tensioned by the straps 40. Alternate loops are then cast off and knitting of the welt proceeded with in the usual manner. At this time there are no buttons on the chain 108 in engagement with the lever 111 and the lever being in the position of Fig. 1, tends to engage the pawl 91 with the toothed surface 93 of the sheave 52 to maintain the sheave stationary against the tension of the weighted cable 55. Just prior to the movement of welt hooks 47 to receive the first course loops a button on the chain 108 engages the lever 135 to shift the rod 121 to the right, as viewed in Fig. 1, and, through lever 122 and rod 121, turn the cam 136 in a counterclockwise direction, as viewed in Fig. 11. This counterclockwise movement brings the cam portions 154 and 157 beneath the stem and pin 156 and 158 respectively, to disengage the pawls 137 and 146 from the ratchet wheel 140. During subsequent knitting of the welt fabric or just prior to the start of a blank, the hooks 47 of straps 46 are attached to the bands 70 and the bands advanced toward the needles to bring the hooks 47 to the position of Fig. 12 and latched as hereinbefore set forth. As the hooks 47 are advanced, the high portion 98 of cam 100 on the shaft 67, turns the lever 101 in the clockwise direction, as viewed in Fig. 5, to engage the collar 106 on rod 95 and disengage the pawl 91 from the toothed portion 93. The hooks 47 and straps 46 are thereby held in latched position under tension exerted by the weighted cable 55.

After a predetermined length of fabric is knitted the welt wire or rod 76 is placed on each fabric in position to be engaged by the hooks 47 of straps 46. At a predetermined point in formation of the welt the pattern means causes the second welt bar operating cam to function to turn shaft 31 and cause the links 33 to engage with and advance the welt bar 27 into the so-called "half-turn" position. This occurs when the welt bar has reached the approximate posi-

tion in which it is shown in Fig. 12 so that there is a relatively free movement of shaft 31 and pins 35 before the pins contact the socket members 36 on the welt bar and advantage is taken of this relatively free movement to cause a cam (not shown) on the shaft 31 to release the latch holding the shaft 67 and for the pattern means, at substantially the same time, to cause a cam follower to be moved to cause a cam (not shown) on the cam shaft to quickly turn shaft 67 and drums 68 to move the spurs 75 on the belts 70 out of the path of the hooks 47 on the draw-off straps 46 operated by shaft 43 and reels 45. As the shaft 67 is turned to move the spurs 75 out of the path of the hooks 47, the low portion 107 of the cam 100 again engages the arm 102 of lever 101 which disengages the arm 103 from the collar 106 on the rod 95. However, just prior to the cycle of movements causing the "half-turn" operation, a button on the chain 108 is brought beneath the projection 116 of lever 111 thereby maintaining pawl 91 in disengaged position relative to the toothed surface 93, when the arm 103 disengages the collar 106, and the tension on the straps 46 as exerted by the cable 55. Sufficient buttons are carried by the chain 108 to keep the weight motor means 48 in action until the spring motor means is brought into action as herein-after set forth. Therefore when released, the straps 46 act on the welt wire 76 to draw the wire against the fabric and as the welt bar 27 is moved to the "half-turn" position by the pins 35, the welt wire forms a fold in and tensions the fabric. From the time the pins 35 engage the socket members 36 on the welt bar 27, the tension exerted by the straps 46, through the welt bar and hooks 30 on the fabric, is transferred to and supported by the pins and only the weight motor means 48 is effective to apply tension to the fabric. Movement of the welt rod to tension the fabric and the movement of the welt bar to "half-turn" position slides the loops along the welt hooks 30 and against elements 160 carried on the stems of the welt hooks. While the welt bar is in its half-way position knitting continues until the welt fabric is completed. The pattern means then causes the third cam, hereinbefore set forth, to actuate the welt bar to move it toward the needle row until the hooks 30 project between the needles to the same extent as at the time of hook-up. The "dwell" of said last cam, is, however, greater than that of the cam used for hooking up. While said third cam holds the welt bar in the desired position the needle bar is tilted away from the press edge more than is ordinarily done in a knitting cycle and the needles from which the loops had been cast off are brought up, through the loops held on the welt hooks 30, the remaining needles being pressed toward the usual presser edge of the machine by the elements 160. The remaining needles are therefore prevented from striking the edge of the fabric and the welt is turned quickly and without damage. All the stocking blanks on the machine are, of course, turned at once. Thereupon, means (not shown) is engaged with shaft 31 to hold it against further turning movement in the take-up direction thereby removing the tension on the welt bar. Immediately following or as soon after the welt is turned as desired the last button on the pattern chain 108 is moved from beneath the lever 135 which acts through rod 121, lever 122 and rod 127 to move the high cam portions 154 and 157 back to the position of Fig. 11 thereby permitting engagement of the

pawls 137 and 146, respectively, with the ratchet wheel 140 to turn the shaft 43 in the clockwise or take-off direction. Immediately following engagement of the pawls 137 and 146 with the ratchet wheel 140, the last button on chain 108 is moved from beneath lever 111 whereby the spring 97 biases the rod 95 to engage the pawl 94 with the toothed surface 93 and arrest the take-off action of the sheave 52 on the shaft 43.

Knitting then continues with the welt bar 27 being drawn by the fabric along the bridge members 25 until it is convenient to disengage the welt hooks 30 from the loops of the fabric. Thereupon, the socket members 36 of the welt bar are placed in engagement with the pins 35 on links 33 and the straps 40 reconnected to the welt bar for the start of a subsequent welt turning cycle.

While a form of mechanism within the invention has been described and its operation indicated as throwing the weight and spring motor means for the main draw-off into action at certain times, it will be understood and will be clear to those skilled in the art that the mechanism herein disclosed is adapted to permit the pattern means to disconnect and activate the weight and spring motor means in any desired sequence. Further, where additional tension on the fabric is required the buttons on the pattern chain may be arranged so as to simultaneously activate both weight and spring motor means.

The improvements specifically shown and described by which the above results are obtained can be changed and modified in various ways without departing from the invention herein disclosed and hereinafter claimed.

I claim:

1. In a full-fashioned knitting machine, the combination of a main draw-off shaft, a weight motor means having connections for driving said shaft when the motor means is active, a member adapted and arranged to deactivate said motor means, means biasing said member into position to deactivate said motor means, a pattern means, and connections between said pattern means and said member adapted to move it against said biasing means, said pattern means including means for operating said second mentioned connections to permit the motor to operate when desired.

2. In a full-fashioned knitting machine in combination, a welt wire, a reel, connecting means for transmitting a draw-off tension from said reel to said welt wire, a weight motor means having connections for driving said reel when the weight motor means is active, spring motor means having connections for driving said reel when the spring motor means is active, pattern means and means controlled by said pattern means for rendering said motor means active to turn said reel at desired times.

3. In a full-fashioned knitting machine, the combination with a welt wire, both weight and spring type motor means, a reel, a shaft for said reel, means for connecting said reel to the welt wire and connections from each of said motor means for driving said shaft, of a pattern means, and means controlled by said pattern means for rendering said motor means active one after the other and for inactivating when desired the first of said motor means to be thrown into action.

4. In a full-fashioned knitting machine, the combination with a welt wire, both weight and spring type motor means, a reel and shaft therefor, means for connecting said reel to the welt wire, and connections from each of said motor

means for driving said shaft, of a pattern means, and means controlled by said pattern means for rendering said motor means effective simultaneously to turn said shaft and for afterward inactivating one of said motor means.

5. In a full-fashioned knitting machine, the combination with a welt wire, both weight and spring type motor means, a reel, a shaft for said reel, means for connecting said shaft to the welt wire, and connections from each of said motor means for driving said shaft, of a pattern means, said weight motor including a circular member, a pawl adapted to cooperate with said member for holding said weight motor means inactive, and connections adapted to be operated by said pattern means for removing said pawl from engagement with said member to permit said shaft to be operated by said weight motor means, and connections adapted to be operated by said pattern means for causing said spring type motor means to operate to turn said shaft.

6. In a full-fashioned knitting machine, the combination with a welt wire, both weight and spring type motor means, a reel shaft therefor, means for connecting said shaft to the welt wire, and connections from each of said motor means for driving said shaft, of a pattern means, said weight motor including a circular member, a pawl for holding said weight motor means inactive, means biasing said pawl into holding engagement with said member, connections adapted to be operated by said pattern means for removing said pawl from engagement with said member to permit said shaft to be operated by said weight motor means and connections adapted to be operated by said pattern means for causing said spring type motor means to operate said shaft.

7. In a full-fashioned knitting machine, the combination with a welt wire, both weight and spring type motor means, a reel and shaft therefor, straps connected to said reel for moving said welt wire in the draw-off direction, and connections from each of said motor means for driving said shaft, of a member forming part of said weight motor and coaxial with said shaft, a pawl for engaging said member to hold said weight motor means inactive, means biasing said pawl into holding engagement with said member, means whereby said straps may be run back toward the needle row into position in which they are adapted to be engaged with said welt wire, a lever means adapted to move said pawl out of holding engagement with said member, means whereby said lever means is operated to render said pawl inoperative to hold said weight motor means, pattern means, a connection between said pattern means and said pawl for moving said pawl out of the path of said member to permit said weight motor means to operate, and connections between said pattern means and said spring type motor means for rendering it inactive and permitting it to become active.

8. A draw-off arrangement for a full-fashioned knitting machine comprising, in combination with a welt wire, both weight and spring type motor means and means for connecting said motor means to the welt wire, of a welt bar having welt hooks thereon for holding loops of the first course of a fabric, means for reversing the movement of said bar and hooks and holding the bar stationary during the knitting of a portion of welt fabric whereby the hooks on the bar act as an abutment to sustain the tension on a bight of fabric, a pattern means, means for normally inactivating said weight motor means,

13

means controlled by said pattern means for acting on said inactivating means to permit the weight motor means to affect the welt wire and to afterward permit the inactivating means to become effective, means whereby said spring motor means may be inactivated or permitted to operate on the welt wire, and means whereby said last mentioned means is controlled by said pattern means so that the spring motor means affects the welt wire as the weight motor means is inactivated.

9. In a full-fashioned knitting machine, the combination with a welt wire, both weight and spring type motor means, a reel and a shaft therefor, straps connected to the reel for moving said welt wire in the draw-off direction, and connections from each of said motor means for driving said shaft, of a member forming part of said weight motor means and coaxial with said shaft, a pawl for engaging said member to hold said weight motor means inactive, means biasing said pawl into holding engagement with said member, means whereby said straps may be run back toward the needle row into position in which they are adapted to be engaged with said welt wire, a lever means adapted to move said pawl out of holding engagement with said member, means for operating said lever means when said straps are run back to render said pawl inoperative to hold said weight motor means, pattern means, a connection between said pattern means and said pawl for moving said pawl out of the path of said member to permit said weight motor means to operate, and connections between said pattern means and said spring type motor means for rendering it active.

10. In a full-fashioned knitting machine, the combination with a welt bar, means for drawing off said welt bar in a take-off direction including means to connect the draw-off means to the welt bar, of a pattern means, a welt wire, both weight and spring type motor means, means including said weight motor means and connections from said weight motor means to said welt wire for applying a take-off tension to said welt wire, means for reversing the movement of said welt bar and moving it against the take-off tension to a half-way position, means whereby said spring motor means may be inactivated or permitted to operate on the welt wire, and means whereby said last mentioned means is controlled by said pattern means so that the spring motor means affects the welt wire as soon as desired after the movement of said welt bar has been reversed.

11. In a full-fashioned knitting machine, the combination of a draw-off reel and a shaft therefor, straps connected to said reel, means to drive said shaft in the draw-off direction, an inactivating member adapted to prevent said means from acting on said shaft, means to turn said reel contrary to the draw-off direction, and a train for transmitting force from said last means to said inactivating member, said last means adapted and acting on said train to transmit force to said inactivating member to move it into a position permitting said shaft to be turned by said last means without hindrance.

12. In a full-fashioned knitting machine, the combination of a draw-off reel and a shaft therefor, a motor means, a driving connection between said motor means and said shaft including an overdrive permitting the shaft to run ahead of said means, another motor means for driving said shaft, pattern means, and connections be-

14

tween said pattern means and said two motor means for transmitting force from the pattern means to determine the starting and stopping of the motor means.

13. In a full-fashioned knitting machine, the combination, a draw-off reel and a shaft therefor, a motor means, a driving connection between said motor means and said shaft including an overdrive permitting the shaft to run ahead of said means, an inactivating member adapted to prevent said means from acting on said shaft, means to turn said reel contrary to the draw-off direction, a train for transmitting force from said last means to said inactivating member, said last means adapted and acting on said train to transmit force to said inactivating member to move it into a position permitting said shaft to be turned by said last means without hindrance, another motor means for driving said shaft, and connections between said pattern means and said two motor means for transmitting force from the pattern means to determine the starting and stopping of the motor means.

14. In a full-fashioned knitting machine, in combination, draw-off reel and a shaft therefor, a motor means including a circular member, a driving connection between said motor means and said shaft including an overdrive permitting the shaft to run ahead of said motor means, means adapted and arranged to act when permitted to prevent said motor means from acting on said shaft and including a pawl biased to engage said circular member, a lever, connections between said lever and said pawl acting when the lever is moved in a certain direction to withdraw the pawl from said circular member, means to turn said reel contrary to the draw-off direction, a train for transmitting force from said last means to said lever when the reel is being turned against the draw-off to move the pawl out of contact with said circular member, a second motor means, connections between said second motor means and said shaft for driving the shaft in the draw-off direction, a pattern means, connections between said pattern means and said lever for moving when desired said pawl against its bias away from said circular member to permit said first motor means to operate said shaft, and connections between said pattern means and said second motor means adapted and arranged to be actuated by the pattern means to hold the second motor means out of action or to permit it to operate said shaft.

15. In a full-fashioned knitting machine, the combination of a main draw-off shaft, a weight motor means having connections for driving said shaft when the motor means is active, a member adapted to inactivate said motor means, means for biasing said member toward a position in which said motor means is inactive, a pattern means, and direct connections between said pattern means and said member adapted to move it against said biasing means, said pattern means including means for operating said second mentioned connections to permit the motor to operate when desired.

16. In a full-fashioned knitting machine in combination, a welt wire, a reel, connecting means for transmitting a draw-off tension from said reel to said welt wire, a weight motor means having connections for driving said reel when the weight motor means is active, spring motor means having connections for driving said reel when the spring motor means is active, pattern means and means directly controlled by said

15

pattern means for rendering said motor means active to turn said reel at desired times.

17. In a full-fashioned knitting machine, the combination with a welt wire, both weight and spring type motor means, a reel, a shaft for said reel, means for connecting said reel to the welt wire and connections from each of said motor means for driving said shaft, of a pattern means, and means controlled by said pattern means for rendering said motor means active one after the other and for inactivating for a material number of knitting cycles when desired the first of said motor means to be thrown into action.

18. In a full-fashioned knitting machine, the combination of a draw-off reel and a shaft therefor, a motor means, a driving connection between said motor means and said shaft including an overdrive permitting the shaft to run ahead of said means, another motor means for driving said shaft, pattern means, and direct connections between said pattern means and said two motor means for transmitting force from the pattern means to determine the starting and stopping of the motor means.

19. In a full-fashioned knitting machine for making stocking blanks, the combination of a draw-off reel and a shaft therefor, a motor means, a driving connection between said motor means and said shaft, another motor means for driving said shaft, pattern means including a plurality of levers, a chain having projections thereon for operating said levers and springs biasing said levers toward the chain, a member for immobilizing said first motor means during a portion of the time the machine is making a blank, a connection between one of said levers and said member, a member for immobilizing said second motor means during a portion of the time the machine is making a blank, and a connection between another of said levers and

16

said second member, said connections, projections, levers and spring adapted and arranged to first throw both motor means into action and to then throw out of action one of the motor means while the other motor means continues to act.

20. In a full-fashioned knitting machine, the combination with a draw-off reel and a shaft therefor of a weight motor means, a driving connection between said motor means and said shaft, a spring motor means for driving said shaft, pattern means including a plurality of levers, stop means for determining the limit of movement of said levers in one direction, springs for biasing said levers against said stop means and a chain having projections thereon for operating said levers to move them away from said stops, a pivoted member adapted to immobilize said weight motor, a linkage between one of said levers and said pivoted member, a member adapted to immobilize said spring motor and a linkage between another of said levers and said second member, said first lever and its linkage being arranged to release said weight motor from its immobilizing member when the lever is operated by a button on said chain and said other lever and its linkage being arranged to move said second member to immobilize the spring motor when the lever is operated by a button on said chain.
